HOLLOW TILE BLOCK

Frank A. Holby, New York, N. Y., assignor to
New Jersey Clay Products, Inc., New York,
N. Y., a corporation of New Jersey

Application September 29, 1933, Serial No. 691,538

1 Claim. (Cl. 72—66)

The present invention relates to a hollow tile block.

The principal object of the present invention is to provide a hollow tile block which is so constructed that removal of portions of the outer webs of the block will not weaken the block.

The hollow tile blocks now ordinarily used comprise two outer webs joined by side walls, suitable additional webs being provided internally of the block to reinforce the same. In the use of such blocks in floor construction, the outer webs referred to become the upper and lower webs of the block. The internal webs ordinarily comprise a central web extending parallel with the upper and lower webs and a number of vertical webs arranged perpendicular to the upper, lower and central webs.

Because of the fact that in the blocks now used, the upper, lower and central webs are parallel, the breakage of any portion of these webs will cause the entire block to be weakened. For example, if any part of the upper web is broken away, the block will be correspondingly weakened. After a building has been entirely constructed, it is frequently necessary to lay piping or other conduits in the flooring. In order to provide a channel for the piping or conduit, it is usual to cut through the flooring or ceiling and to break away portions of either the upper or lower webs of the blocks so that the piping or conduit may be placed within the space provided in the blocks. This naturally results in a weakening of the entire floor structure.

The block of the present invention includes an arched central web, preferably of concave-convex formation, instead of the usual central web extending parallel with the upper and lower webs. The provision of an arch in the block permits either the upper or lower webs to be partially broken away without in any way affecting the strength of the block and the flooring of which it forms a part.

Hollow tile blocks including arched webs, either concavo-convex or arranged in truss formation, have heretofore been provided, but, in these structures, the curved web or the webs of truss formation have been so arranged with respect to the upper and lower webs of the block that portions thereof merge with or intersect either the upper and lower webs, or both. With the block constructed in that manner, it has been possible to break away only certain portions of the upper and lower webs, these portions being those which are farthest removed from the point of intersec-

tion or merger of the upper or lower webs with the curved or truss webs.

Individual hollow tile blocks arranged to be assembled in such a manner that they will coact to form an arch, have also been heretofore provided. In this type of construction, each block of the arch is arched and the blocks are generally of a different formation in order that the completed arch will have the desired form. Each block, therefore, requires a mold of an individual shape for its production. Also, in the construction of the arch, the blocks must be placed in the proper arrangement and a form must be constructed to support the blocks while setting them. Such blocks are naturally more expensive in production and the time and extra material required for their assembly affects the cost of the building in which they are used. In any event, blocks of this type have only a specialized use and cannot be included in a flooring of the usual type.

Another important object of the invention is to provide a hollow tile block including an arched web, which block is so designed that it may be used in the ordinary type of flat floor construction and which is inexpensive in manufacture and may be readily positioned in the flooring.

Another important object of the invention is to provide a hollow tile block including an arched web, which web is so arranged within the block that it cannot be fractured by cutting of a channel at any point on the upper and lower surfaces of the block which can be reached from the corresponding surfaces of the flooring.

The provision of an arched web within a block in such a manner that every point of this web will be spaced from the upper and lower webs, is of particular importance because of the fact that when an initial cut is made in the flooring, the person making the cut has no way of knowing the exact position of the individual blocks in the flooring and therefore, if blocks of the prior art type are used, may inadvertently cut into either the springing point or highest point of the curved web or truss web used in the block.

Other objects and advantages of the invention will appear from the following specification and drawing.

In the drawing,

Figure 1 is a perspective view, in section, showing a flooring constructed of the blocks of my invention, and

Figure 2 is a view, in perspective, showing one of the blocks of the invention.

The numeral 10 generally designates the block of my invention, which block comprises upper and

lower webs 11 and 12, respectively, and a central arched web 13. The upper and lower webs are joined by side walls 14 and 15 and the lower longitudinal edges of the block may be provided 5 with supporting shoulders of the usual construction.

A central vertical web 16 extends longitudinally of the block and vertical longitudinal webs 17 are also provided between the vertical web 16 and the side walls of the block. It will be observed that the outer edges or springing points 10 of the arched web 13 are spaced somewhat above the lower web 12 of the block and that the highest point of the arched web 13 is spaced 15 downwardly along the central vertical web 16 from the upper web 11.

As is shown in Figure 1, in the construction of 20 flooring by means of a block constructed in accordance with my invention, the supporting shoulders at the lower side edges of the block rest upon the lower angled flanges of supporting members 20 of the type generally used in such structures, the arrangement of the supporting shoulders on the blocks and the inwardly inclined side walls 14 and 15 permitting the blocks 25 to be readily positioned between the supporting means 20.

A layer 21 of concrete may be poured over 30 and between the blocks after they have been positioned between the supporting beams and a coating 22 may also be applied to the lower surface of the blocks to form a ceiling.

After the blocks have been secured in position by concrete, should it become necessary to place 35 conduits or piping in the flooring, a channel may be cut either in the flooring 21 or ceiling 22, which channel may extend through the upper or lower webs of the blocks. In Figure 1, a pipe or conduit 30 is shown laid in the upper portion of 40 one of the blocks, between the central vertical web 16 and the next adjacent vertical web 17. If, during the operation of breaking away, the 45 portion of the upper web 11 between the vertical webs 16 and 17, a portion of either web 16 or 17 should be broken, such breakage will not extend into the arched web 13 to thereby weaken this web. In other words, because the highest point 50 of the arched web 13 is spaced beneath the upper web 11, there is sufficient space between these two webs to permit of a range of error in breaking into the block. It will be appreciated that this feature is of considerable importance, par-

ticularly since it is difficult, in actual practice, to break the flooring and block in a straight line. Also, when the initial cut is made in the flooring, the person making the cut does not know the exact position of the vertical webs in the flooring. It is often necessary to lay piping or conduits in such a way that the vertical webs must be partially broken away. This can obviously be done without in any way weakening the blocks through which the piping extends.

Figure 1 also shows, at 31, a piping or conduit 10 laid in the lower portion of the block between the side wall 15 and the vertical web 17. Because the springing point of the arched web 13 is spaced above the lower web 12, no portion of the arched web 15 will be broken by the cutting of a channel in the lower web of the block.

There is also illustrated, at 32 in Figure 1, a pipe or conduit laid in the upper portion of one of the blocks between the side wall 14 and the 20 adjacent vertical web 17.

It will be understood from the above that the webs or side walls of the blocks of my invention may be broken into at any point which may be reached from the upper or lower surface of the 25 flooring or block without fracturing the arched web of the block and thereby weakening the block. Furthermore, no channel cut at such points can weaken the block. The result is that a flooring, formed of the blocks of the invention 30 will be equally as strong, with a channel cut at any portion which can be reached from the upper and lower surfaces of the flooring, as a block of the usual construction.

It is to be understood that the invention is 35 not limited to the details of construction shown in the drawing and described in the specification and that the example given does not include all of the uses of which it is capable; also that the phraseology employed in the specification is for 40 the purpose of description and not of limitation.

I claim:

An integral hollow tile block comprising outer webs, side walls joining the edges of the outer webs, an arched web joining the side walls, each 45 side wall including a shoulder adjacent one outer web, the springing point of the arched web being between the shoulders and the opposite outer web, the shoulders being adapted to bear upon supporting members, and the body portion of the 50 arched web being spaced from the outer webs.
